FIGURE 1 is a front perspective view of a combined razor and blade package holder or similar article embodying my new design.

The blade package, razor and fragmentary portion of a shelf, disclosed in broken lines in FIGS. 1 and 2, are included for illustrative purposes only.

1 claim:

The ornamental design for a combined razor and blade package holder or similar article, as shown and described.
